Primary Examiner — Brian N Vinson(74) *Attorney, Agent, or Firm* — Fish & Tsang LLP(57) **CLAIM**

What is claimed we claim the ornamental design for an electric candle, as shown and described.

DESCRIPTION

FIG. 1 is a top, front, right side perspective view of a first embodiment of the electric candle of the new design.
 FIG. 2 is a rear elevation view of the first embodiment of the electric candle of the new design.

FIG. 3 is a front elevation view of the first embodiment of the electric candle of the new design.

FIG. 4 is a left side elevation view of the first embodiment of the electric candle of the new design, of which the right side is a mirror image thereof.

FIG. 5 is a top plan view of the first embodiment of the electric candle of the new design; and,

FIG. 6 is a bottom plan view of the first embodiment of the electric candle of the new design.
